(57) CLAIM

The ornamental design for a bowl with lid, as shown and described.

DESCRIPTION

FIG. 1 is a perspective view of a bowl with lid according to my new and ornamental design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dash-dot broken lines represent the boundaries of the claimed design and form no part of the claim. The evenly dashed broken lines represent portions of the bowl with lid that form no part of the claimed design.

1 Claim, 5 Drawing Sheets
